UNITED STATES PATENT OFFICE

ALEXANDER N. HIRTH, OF CLIFFSIDE PARK, NEW JERSEY, ASSIGNOR TO W. S. EMBROIDERY WORKS, INCORPORATED, OF CLIFFSIDE PARK, NEW JERSEY

DESIGN FOR AN EMBROIDERED LACE

Application filed February 18, 1930. Serial No. 34,588. Term of patent 3½ years.

To all whom it may concern:

Be it known that I, **ALEXANDER N. HIRTH**, a citizen of the United States, residing at Cliff-side Park, in the county of Bergen and State of New Jersey, have invented a new, original, and ornamental Design for an Embroidered Lace, of which the following is a specification, reference being had to the accompanying drawing, forming part thereof.

The figure is a plan view of a piece of embroidered lace showing a unit of my new design which is to be repeated throughout any desired length of lace.

I claim:

The ornamental design for an embroidered lace substantially as shown and described.

ALEXANDER N. HIRTH.
